[57] ABSTRACT

A movable contact blade of an electric circuit breaker is connected in series with a bimetallic strip forming a part of a tripping device. An arc current shunting blade is stacked on the contact blade, insulated therefrom, and connected to a load terminal strap in shunting relationship to the bimetallic strip. An arc which occurs during interruption of a severe overload current is transferred from the contact blade to the arc current shunting blade, causing the high current to bypass the bimetallic strip.

ELECTRIC CIRCUIT BREAKER WITH ARC CURRENT SHUNTING BLADE STACKED ON CONTACT BLADE

This invention is an improvement of the circuit breaker disclosed in U. S. Pat. No. 3,341,791, issued Sept. 12, 1967, to which reference may be had for a complete description of the circuit breaker parts unrelated to the present improvement.

A problem arises in circuit breakers of low rating, because a bimetallic strip of sufficiently small cross section for good response to low overload currents is likely to be damaged by severe overload currents. This problem has been solved in the past by relatively complicated structures including a second set of contacts which close upon incidence of severe overload current to bypass the current around the bimetallic strip. The present invention relates to a simple arrangement for bypassing severe overload or fault currents around a bimetallic strip without the provision of a second set of contacts and separate operating structure therefor.

An object of the invention is to provide a simple, inexpensive structure for shunting a bimetallic strip of a circuit breaker upon incidence of severe overload or fault currents.

Other objects and advantages will become apparent upon consideration of the following specification along with the accompanying drawings in which:

FIG. 1 is a fragmentary longitudinal sectional view of a circuit breaker constructed in accordance with the invention, certain portions being omitted for clarity;

FIG. 2 is an enlarged perspective view of an insulator between a contact pressure spring and an arc current shunting blade of this invention;

FIG. 3 is an enlarged perspective view of one of two insulating retainers between a movable contact blade and the arc current shunting blade of this invention;

FIG. 4 is an enlarged perspective view of the contact pressure spring;

FIG. 5 is an enlarged perspective view of the arc current shunting blade; and

FIG. 6 is an enlarged perspective view of the movable contact blade.

With reference to the drawings, FIG. 1 discloses a circuit breaker 10 including a load terminal strap 12 having one end of a bimetallic strip 14 secured to an inner end thereof. The other end of the bimetallic strip 14 is connected by a braided wire 16 to a pivotally mounted end of a movable contact blade 18 having a movable contact 20 secured to the other end thereof for cooperation with a stationary contact 22 secured to a line terminal strap 24 along with an arc runner 26.

In accordance with the invention, the movable contact blade 18 is shaped as best shown in FIG. 6 and has an arc current shunting blade 28, best shown in FIG. 5, mounted thereon. The arc current shunting blade 28 has an arcing contact 30 secured to one end thereof. The other end of the arc current shunting blade 28 is connected by a braided wire 32 to the load terminal strap 12 in shunting relationship to the bimetallic strip 14. A tubular insulating sheath 34 is provided on the wire 32. The blade 28 is mounted on the blade 18 by means of a pair of spool-shaped insulating retainers 36, one of which is best shown in FIG. 3. Arcuate recesses 18a and 28a (FIGS. 5 and 6) are provided respectively on the blades 18 and 28 for reception of one of the retainers 36, and arcuate recesses 18b and 28b are pro-

vided respectively on the blades 18 and 28 for reception of the other retainer 36. The recesses 18a and 18b are provided respectively on a pair of edge surfaces 18c and 18d extending substantially at right angles to each other and forming an outside corner portion of the blade 18. The recesses 28a and 28b are provided respectively on a pair of edge surfaces 28c and 28d extending substantially at right angles to each other and forming an inside corner portion of the blade 28 complementary to the outside corner portion of the blade 18.

The blades 18 and 28 are provided respectively with contact mounting surface 18e and 28e on which the contacts 20 and 30 are respectively mounted. The edge surfaces 18e and 28e form equal acute angles respectively with the edge surfaces 18d and 28d, and when the blade 28 is in mounted position on the blade 18, the edge surfaces 18e and 28e are substantially coplanar. The contacts are shaped and mounted in a manner such that the contact 30 forms a continuation or extension of the contact 20, except for a small air gap between them.

The blade 28 is held in position also by contact pressure spring 38 best shown in FIG. 5 by a and having end portions 38a and 38b anchored in a crossbar 40 and a transverse portion 38c bearing on a channel shaped insulator 42 best shown in FIG. 2 and mounted in a notch 28f of the blade 28.

An arc occurring between the contacts 20 and 22 upon opening of the circuit breaker under severe overload or fault conditions tends to travel outwardly, to the left as viewed in FIG. 1, whereupon it establishes itself between the contacts 22 and 30. The arc current at that time flows through the blade 28 and wire 32, rather than through the blade 18, wire 16, and the bimetallic strip 14. The bimetallic strip 14 is thus protected against excessive arcing currents.

Other parts of the circuit breaker 10 may be as disclosed in the aforementioned patent. Briefly, upon the occurrence of a sustained moderate overload, the free end portion of the bimetallic strip 14 will move upwardly, as viewed in FIG. 1, to rotate a common trip bar 44 clockwise and release an intermediate latch member 46 for clockwise movement, whereupon a trip member 48 pivots clockwise to collapse pairs of toggle link members 49 and 50. The link members 50, only one of which is shown in FIG. 1, are connected to a driving bracket 52 for the crossbar 40, and collapse of the toggle link members causes the crossbar 40 to move the blades 18 and 28 and open the contacts 20 and 22.

Upon the occurrence of severe overload or fault currents, the common trip bar 44 is rotated clockwise instead by an actuating member 54 secured to an armature rod 56 carrying an armature member 58 attracted toward a magnetic core member 60 upon flow of the excessive current through the load terminal strap 12.

Various modifications may be made in the structure shown and described without departing from the spirit and scope of the invention.

I claim:

1. An electric circuit breaker comprising a movable contact blade connected in series with a bimetallic strip and a terminal strap, and an arc current shunting blade stacked on the movable contact blade, insulated therefrom, and connected to the terminal strap in shunting relationship to the bimetallic strip.

2. An electric circuit breaker as claimed in claim 1 including a pair of movable contacts mounted respectively on the blades.
3. An electric circuit breaker as claimed in claim 2 including a pair of spool-shaped insulating retainers insulating the blades from each other.
4. An electric circuit breaker as claimed in claim 3 wherein each blade has a pair of arcuate recesses and each spool-shaped insulating retainer is received in one recess on one blade and one recess on the other blade.
5. An electric circuit breaker as claimed in claim 4 wherein the movable contact blade has a pair of edge surfaces extending substantially at right angles to each other, forming an outside corner portion, and each having one of the arcuate recesses therein, and the arc current shunting blade has a pair of edge surfaces extending substantially at right angles to each other, forming an inside corner portion complementary to the outside corner portion of the movable contact blade, and each having one of the arcuate recesses therein.
6. An electric circuit breaker as claimed in claim 5 wherein each blade has a contact-mounting edge surface on which its contact is mounted and the contact-mounting edge surfaces are substantially coplanar.
7. An electric circuit breaker as claimed in claim 6 wherein the contact-mounting edge surface of one blade forms an acute angle with an edge surface thereof having one of the arcuate recesses therein, and the contact-mounting edge surface of the other blade forms an equal acute angle with an edge surface thereof having one of the arcuate recesses therein.
8. An electric circuit breaker as claimed in claim 2 wherein each blade has a contact-mounting edge surface on which its contact is mounted and the contact-mounting edge surfaces are substantially coplanar.
9. An electric circuit breaker as claimed in claim 8 wherein the contact-mounting edge surface of one blade forms an acute angle with another edge surface of the respective blade, and the contact-mounting edge surface of the other blade forms an equal acute angle with another edge surface of the respective blade.
